United States Patent Office.

WILLIAM GILBERT, OF CATSKILL, NEW YORK.

Letters Patent No. 74,341, dated February 11, 1868.

IMPROVEMENT IN MACHINE FOR CUTTING TURF OR SODS.

The Schedule referred to in these Letters Patent and making part of the same.

TO ALL WHOM IT MAY CONCERN:

Be it known that I, WILLIAM GILBERT, of Catskill, in the county of Greene, and in the State of New York, have invented certain new and useful Improvements in Machine for Cutting Turf or Sods; and do hereby declare that the following is a full, clear, and exact description thereof, reference being had to the accompanying drawings, and to the letters of reference marked thereon.

In the annexed drawings, making part of this specification, A represents the frame of the machine, which may consist of a beam with a forked end, as in Figure 2, or of two beams, with their forward ends bevelled, and secured together, so as to make a frame similar to an ordinary triangular cultivator-frame, as seen in Figure 1.

B B represent the handles to this frame. C represents a knife or cutter, which has its two ends turned up at right angles, so that two vertical edges and a horizontal edge may be formed upon it. The knife is secured to the frame by means of screws or bolts, which pass through these upturned ends. The vertical edges are seen from x to x', and the horizontal edge from x' to x'. The horizontal portion of the knife is intended to run under the sod, severing it from the earth, while the vertical knives cut it on each side, from the contiguous sod, of which it formed a part. D represents a horizontal shaft, which lies crosswise of the frame; and above the knife C. On each end of this shaft is a small wheel or roller, I, which rolls upon the earth, and regulating the depth to which the knife enters beneath the sod. An adjustable cutter, e, may be placed on the shaft D, and secured in any desired position by means of a thumb-screw. The object of this knife is to cut the sod in strips when it is desirable. The shaft D passes through slots in the upturned ends of the knife C, and has its bearing in bolts with eyes in their lower ends, which depend from the under side of the frame. The shaft can be raised or lowered, so that the sod may be cut thinner or thicker, as may be necessary.

What I claim as new, and desire to secure by Letters Patent, is—

The knife C and shaft D, with its rollers and knife e, used with the frame A, substantially as and for the purpose set forth.

In testimony that I claim the foregoing, I have hereunto set my hand and seal, this 14th day of December, 1867.

WILLIAM GILBERT. [L. S.]
